(57) CLAIM

We claim the ornamental design for a golf club head, as shown and described.

DESCRIPTION

FIG. 1 is a perspective view of a golf club head, as viewed from the rear, bottom and toe side, according to one embodiment.

FIG. 2 is a perspective view of the golf club head, as viewed from the rear, bottom and heel side, according to the embodiment of FIG. 1.

FIG. 3 is a front elevation view of the golf club head of FIG. 1.

FIG. 4 is a rear elevation view of the golf club head of FIG. 1.

FIG. 5 is a side elevation view of the toe of the golf club head of FIG. 1

FIG. 6 is a side elevation view of the heel of the golf club head of FIG. 1.

FIG. 7 is a top plan view of the golf club head of FIG. 1; and, FIG. 8 is a bottom plan view of the golf club head of FIG. 1. The dashed lines in the drawings are for illustrative purpose only and form no part of the claimed design.
